ATTORNEYS

UNITED STATES PATENT OFFICE.

CHARLES OSCAR TRACY, OF NORWICH, CONNECTICUT.

LOCK.

1,360,057.

Specification of Letters Patent. Patented Nov. 23, 1920.

Application filed January 3, 1920. Serial No. 349,164.

To all whom it may concern:

Be it known that I, CHARLES OSCAR TRACY, a citizen of the United States, and a resident of Norwich, in the county of New London and State of Connecticut, have invented a new and Improved Lock, of which the following is a full, clear, and exact description.

This invention relates to locks, and has for an object to provide an improved construction in which a sliding hasp is used to connect the different parts of the lock mechanism, and has a retaining member for holding two doors or other devices together.

Another object in view is to provide a lock substantially of the padlock type in which a sliding hasp is utilized, the arrangement being such that the hasp slides radially inwardly and outwardly to a locked and unlocked position respectively.

A further object of the invention is to provide a lock in which the hasp is supported against the action of a hammer or other implement by a plurality of supporting members independent of the locking catch.

Another object of the invention is to provide a lock in which a sliding key is used, and a pivotally mounted catch associated with a sliding bolt, the arrangement being such that the bolt is locked when slidably moved into a locked position and unlocked when the key is slidably moved to a given position.

In the accompanying drawing:

Figure 1 is a top plan view of a lock disclosing an embodiment of the invention, the same being shown applied.

Fig. 2 is a sectional view through Fig. 1 on line 2—2.

Fig. 3 is a sectional view through Fig. 2 on line 3—3.

Fig. 4 is a sectional view similar to the right end of Fig. 3, but with the catch shown in an unlocked position.

Fig. 5 is a fragmentary sectional view through Fig. 4 on line 5—5.

Fig. 6 is a detail perspective view showing the key guide embodying certain features of the invention.

Referring to the accompanying drawing by numerals, 1 and 2 may indicate doors which are to be locked together, or any other article or device desired. The lock connecting these doors is formed in two principal parts, namely the hasp section 3 and the lock

section 4. The hasp section 3 is provided with a casing 5 similar in outside appearance to the casing 6 of the lock section 4, though interiorly it is quite different. As shown in Figs. 2 and 3, section 3 is provided with a bottom 7 having a slot 8 merging into an enlargement or head 9 through which the head 10 of the bolt 11 is passed when being adjusted to the position shown in Fig. 2. When the bolt 11 is extending at right angles to the bottom 7 the head 10 thereof will not pass through the opening 9 nor the slot 8, but will clamp section 3 in position. Preferably the clamping action is such that the section may easily slide together with the hasp or bolt 12. It will be noted that the hasp or bolt 12 is provided with an arc-shaped flange or enlargement 13 fitting against the casing 6 while the bolt 14 extends through a suitable slot 15 in casing 6 so that the shoulder 16 will interlock with the hook 17 of the locking catch 18. The head 14 is also provided with an arc-shaped recess 19 for accommodating the bolt 20, which bolt is formed with a head 21 fitting into a recess 22 in the top of the casing 6, while the body of the bolt extends through casing 6 and also through door 1 so as to receive the clamping nut 23 and rigidly clamp the casing 6 in place. The casing 6 is preferably provided with a bottom 24 which is removably arranged in the casing 6, and is provided with a short extension 25 fitting into the notch 15 below the head 14, whereby the bottom cannot be rotated independent of the casing 6, nor can the casing 6 be rotated independent of the bottom. To prevent rotation of the casing 6 and bottom 24, a plurality of pressed out spurs 26 are provided, which are forced into the door 1, said spurs co-acting with bolt 20 to prevent any rotary movement, or in fact any movement whatever of the casing and the bottom. The catch 18 is pivotally mounted on a shaft 27 so as to freely swing thereon, said catch being acted upon by spring 28 so as to always have a tendency to move to the position shown in Fig. 3. The catch 18 is provided with an arm 29 having a plurality of arc-shaped fingers 30, acting in the capacity of tumblers, said fingers being arranged in different planes as shown in Fig. 5, so as to pass through the various openings 31 in a key 32 and also through the various openings 33 in the key guide or ward 34. It will be noted that the spring

28 holds the case in a locked position whenever possible, and when in such a position (Fig. 3) the tumblers 30 will be projecting slightly into the ward 34, but not into the path of movement of the key, when the key is forced in it may freely pass the tumblers so as to engage the catch near point 35 without any hindrance from the tumblers. If an improper key is inserted it will move 10 in until it contacts with the catch at point 35, but cannot move the catch as any pivotal movement of the catch in a direction for releasing the same will cause the fingers or tumblers 30 to press against the key. This 15 will prevent any swinging movement of the catch if the key is an improper one, but if it is provided with the proper slots 31 said slots will come opposite the openings 33 and permit the passage of the tumblers 30. In 20 order to change the combination, the ward 34 is arranged in a slot in the bottom 24 and held therein by rivets or in any other desired manner. It is intended that this ward should be positioned at different points in 25 the slot according to the combination desired, though if preferred it could be always arranged at the same place and the slots or openings 33 varied. It is, of course, understood that the position of the fingers or tumblers 30 would be varied to agree with the 30 position of the slots 33.

What I claim is:

1. A lock of the character described comprising a bolt formed with a notch, a lock 35 casing having an opening through which the bolt passes, a catch pivotally mounted in the casing formed with a hook-shaped portion for interlocking with said bolt so that the hook will fit into said notch, said catch being 40 formed with a projection, and a plurality of fingers extending from said projection, a ward arranged adjacent said projection, said ward formed with a plurality of substantially transverse notches for accommodating 45 said fingers, and said fingers passing through said notches when the catch is moved to a disengaged position.

2. A lock comprising a sliding hasp formed with a bolt head having a hood at one end and said hood having a substantially 50 T-shaped slot in the bottom, means formed with a head extending through said slot for clamping the hasp to a body so that the hasp may slide and also rotate after being disengaged, a lock casing fitting over said bolt head, and means in the casing for interlocking with the bolt head.

3. A lock comprising a bolt formed with a notch for receiving a catch having an arc-shaped notch in the end, said bolt having an 60 arc-shaped shoulder, a lock casing fitting against said arc-shaped shoulder, a clamping bolt extending through the casing and fitting loosely against a notch in the end of the bolt, a pivotally mounted catch for locking said bolt and engaging the bolt in said notch, and means for guiding a key into the casing for disengaging the catch.

4. A lock comprising a bolt, a casing into which the bolt projects, a pivotally mounted 70 catch adapted to hold the bolt in a locked position, a ward for guiding a key into said catch for actuating the same, said ward being formed with a plurality of substantially transverse slots, and a plurality of arc-shaped fingers connected with said catch 75 movable through said slots when said key disengages said catch whereby the key must be of the correct shape to permit the passage of said fingers before said catch can be disengaged.

5. A lock of the character described comprising a casing, a catch arranged in said casing for engaging a bolt, a ward connected with the bottom of the casing and formed so 85 as to be positioned at different points in said bottom for varying the combination, said ward being formed with a plurality of notches, and a plurality of fingers connected with said catch movable through said 90 notches when the catch is operated by said key.

CHARLES OSCAR TRACY.
